FREEZER CABINET

Robert R. Fink, Duluth, Minn., assignor to International Telephone and Telegraph Corporation, a corporation of Maryland

Application February 4, 1953, Serial No. 23,446

Term of patent 7 years

(Cl. D67—3)

To all whom it may concern:

Be it known that I, Robert R. Fink, a citizen of the United States, residing at Duluth, State of Minnesota, have invented a new, original, and ornamental Design for a Freezer Cabinet, of which the following is a specification, reference being had to the accompanying drawings, forming a part hereof.

Figure 1 is a perspective view of a freezer cabinet showing my design in a closed position, and

Figure 2 is a perspective view thereof in an open position.

The essential features of the design reside in

the portions shown in full lines. The other side of the cabinet is substantially similar to the one shown in the drawing.

I claim:

The ornamental design for a freezer cabinet, substantially as shown and described.

ROBERT R. FINK.
